Primary Examiner—M. N. Pandozzi*Attorney, Agent, or Firm*—Hill & Simpson**[57] CLAIM**

The ornamental design for a drinking glass, as shown and described.

DESCRIPTION

FIG. 1 is a perspective view of a drinking glass in accordance with the present invention; and,

FIG. 2 is a side view of the drinking glass of FIG. 1 with all sides being symmetrical.

The drinking glass is particularly used for beer drinking and, as illustrated in the photos, is symmetrical in shape.
